UNITED STATES PATENT OFFICE.

DANIEL KOPS, OF NEW YORK, N. Y.

APPAREL-CORSET.

1,400,294.

Specification of Letters Patent. Patented Dec. 13, 1921.

Application filed November 16, 1920. Serial No. 424,340.

To all whom it may concern:

Be it known that I, DANIEL KOPS, a citizen of the United States, residing in the borough of Manhattan, city, county, and State of New York, have invented an Improvement in Apparel-Corsets, of which the following is a specification.

At the present time and in an effort to conform to the prevailing styles and fashions there is an effort among women both stout and slender to make themselves appear more slender than they are in reality, and in the cases of thin women the tension applied to the body by the corset garment to produce this effect oftentimes bears against the hip bone with a sufficient pressure to be painful and many times in such a manner as to be injurious. The object therefore of the present invention is to overcome this difficulty by providing a corset garment in which in the sides thereof there are provided concave sections adapted to conform to the hip bones of the wearer in such a manner as to relieve the pressure which would otherwise be exerted against the hip bones and to enable the wearer to use the corset to produce the desired slender appearance without any injurious bodily effect.

In carrying out the invention to produce the desired effect the corset garment is preferably made in halves to be connected at the front by the usual clasps and at the back by the customary adjusting laces and the central or side portion of each corset body half is made in parts preferably three in number and extending from the top to the bottom of the garment and so shaped and connected, as hereinafter described, as to form a circumferential concave section into which the hip bone of the wearer is adapted to fit so that no undue pressure in the use of the garment will be brought to bear against the hip bone.

In the drawing:

Figure 1 is a perspective view illustrating the use of the corset garment made in accordance with this invention, and

Fig. 2 is an enlarged plan view of one half of the garment.

Referring particularly to the drawing and as hereinbefore stated, the corset made in accordance with this invention is made in the usual corset body halves which are designated by 10 and 11 respectively. As is customary these corset body halves in the front portions are provided with steels 12, one of

which is fitted with the usual stud members 13 and the other with the usual socket members to be engaged the one with the other in connecting the halves of the garment at the front thereof. Also as is customary, the halves of the garment at the back are fitted with series of eyelets 15 to receive the adjusting laces as commonly employed in securing the garment in position on the body of the wearer. In this corset also the corset body halves thereof are provided with depending skirt members which are indicated respectively at 16 and 17. As shown in the drawing the front portion of each corset body half is provided with stays 18 that are suitably placed therein, and the back portion of each corset body half with stays 19 which are suitably placed therein.

The central portion of each corset body half or that part thereof which lies at the side of the wearer is preferably made in sections so shaped and connected as to have a concave section for the reception of the hip of the wearer. It will be understood that the number of parts comprising this central portion of each corset body half may be varied, although as illustrated I prefer to make this central portion in three parts as indicated, the central part being designated by 20 and the parts lying on either side thereof by 21 and 22. These parts of the central portion extend from the upper edge of the garment through the body portion thereof and to the lower edge of the skirt member and the central part 20 at the lower end is pointed as indicated at 23 and the edges thereof diverge upwardly with curved portions 24 and 26, the curvature of which gradually decreases until at points above the waistline the edges of this central member are substantially straight and continue so to the upper edge of the garment as indicated at 25 and 27. The outer parts 21 and 22 of the central portion are correspondingly shaped but reversely placed, diverging from the upper edge of the corset downwardly to the lower edge of the skirt member and these parts are connected to one another by lines of stitching indicated respectively at 28 and 29, being thus shaped, as will be understood, and connected the one to the other that the central or side portion of each corset body half is made to provide a circumferential concave section 30 which conforms to and into which the hip bone of the wearer is adapted to fit and lie so that no undue pres-

105

110

sure in the use of the garment is brought to bear against the hip bone. Also as indicated in the drawing the front portions of the corset body halves may be fitted with 5 hose supporter straps 31 and preferably I also employ hose supporter straps attached to the lower edge of the skirt section at the base of the central part 20, these hose supporter straps being indicated at 32.

10 I claim as my invention:

1. An apparel corset comprising corset body halves each having depending skirts, and a side portion made of component parts each extending from the upper edge of the 15 garment to the lower edge of the skirt and formed and connected to provide a circumferential concave section for fitting over the hip bone of the wearer to relieve the pressure otherwise placed thereon in the use of 20 the garment.

2. An apparel corset comprising corset body halves each having depending skirts, and a side portion made of a central and two adjacent parts each extending from the upper edge of the garment to the lower edge 25 of the skirt member, the central part being pointed at its lower end and having its edges diverging upwardly and curved for a predetermined distance and thereafter extending substantially straight to the upper edge of 30 the garment, with the adjacent members connected to the central member to form a circumferential concave section therein at the curved edge portions thereof to fit over the hip of the wearer to relieve the pressure 35 which would otherwise be placed thereon in the use of the garment.

Signed by me this 1st day of November, 1920.

DANIEL KOPS.
